UNITED STATES PATENT OFFICE.

WILLARD BARTLETT, OF PARIS, FRANCE, ASSIGNOR TO AMERICAN CHICLE COMPANY,
OF LONG ISLAND CITY, NEW YORK, A CORPORATION OF NEW JERSEY.

DISPENSING COVER FOR CONTAINERS.

Application filed November 11, 1924. Serial No. 749,152.

The object of the invention is to provide a dispensing cover for tins and other containers, the device being particularly adapted for the dispensing of small units or powder.

5 An application of the invention is to serve as a cover for small tins of pastilles and a primary object of the invention is the provision of a device of the kind which shall have maximum simplicity and low cost, to 10 enable it to be used where the price for the tin of pastilles is very low and will warrant, in some cases, only a fraction of a cent in the cost of the tin cover and dispensing device.

The invention will be understood by reference to the accompanying drawings, in 15 which—

Figure 1 is a plan view of the cover from the front face thereof.

Figure 2 is a plan view of the cover from 20 the rear face thereof, and

Figure 3 is a plan view of the formed "blank" for the closure member.

By reference to the drawings it will be seen that the cover 3 for the tin or other 25 container is provided with a discharge opening 1 and an arcuate slot 2.

In the rear of the cover 3 is disposed the closure member 4, the latter member being provided with a finger 8, an extension of 30 which projects through slot 2.

Closure member 4 is provided with a rear extension 5 which is cut to form projecting ears 6. Ears 6, in assembling the device, are bent upwardly, and pass through a round 35 opening 9 formed in the cover 3. The ears are then bent downwardly upon the outer face of the cover so as to hold the closure against displacement while permitting it to swing about opening 9 as an axis.

40 In practice, closure member 4 may be

formed of light gauge tin so that the ears 6 and finger piece 8 may readily be bent upward by hand, if desired, and the closure applied to the tin cover 3 by unskilled, and, therefore, inexpensive labor.

45 It is to be noted that the only machinery required in the construction of the device is a cutting die for the closure blank and a cutting die for forming the two round openings and the arcuate opening in the cover. 50 Rivetting operations are dispensed with and it is this item which is one of the principal reasons for the low cost of the device.

It will be understood that the discharge opening may be of any desired form and that 55 the ears and hole of the pivot device may be reversed in position, in that the hole may be formed in the closure member and the ears on the cover, if desired, such modifications being within the spirit of the invention.

60 What I claim and desire to secure by Letters Patent is as follows:

A dispensing cover comprising a flat plate formed with an arcuate opening, a dispensing opening adjacent thereto and a pivot 65 opening adjacent the dispensing opening, a substantially flat fan-shaped plate having near its end of lesser width transversely projecting ears, projected through the pivot opening, and at the front end a forwardly 70 projecting ear passing through the arcuate opening, the intermediate portion of the plate being adapted to normally cover the dispensing opening and to expose said opening when the plate is moved laterally a pre-determined distance.

75 In testimony whereof, I have signed my name to this specification.

WILLARD BARTLETT.
